UNITED STATES PATENT OFFICE.

ARTHUR A. ARNOLD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

CUTTER.

1,267,836.

Specification of Letters Patent. Patented May 28, 1918.

Application filed January 5, 1917. Serial No. 140,849.

To all whom it may concern:

Be it known that I, ARTHUR A. ARNOLD, a citizen of the United States, residing at Southbridge, in the county of Worcester and State of Massachusetts, have invented certain new and useful Improvements in Cutters, of which the following is a specification.

This invention relates to improvements in cutting machines and has particular reference to an improved machine particularly adapted for the cutting of ophthalmic lenses.

One of the leading objects of the present invention resides in the provision of a cutter for ophthalmic lenses or the like, which will facilitate to the greatest possible extent the interchanging of guiding formers for the cutter.

A further object of the invention is the provision of an improved cutter in which moving parts and joints liable to become loose are reduced to a minimum.

A further object of the invention is the provision of an extremely simply constructed rigid and accurate lens cutter.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a perspective view of my complete cutter.

Fig. II represents a vertical longitudinal sectional view thereof.

Fig. III represents a plan view, the standard being shown in section.

Fig. IV represents a detailed perspective view of the former securing mechanism.

Fig. V represents a fragmentary detailed sectional view of a slight modification of my construction.

Fig. VI represents a fragmentary plan view thereof.

In the drawings, in which similar characters of reference are employed to denote corresponding parts throughout the several views, the numeral 1 designates the base, block or frame of my improved cutter having the basal ears 2 adapted to receive se-

curing devices to retain the drill in position 55 on the bench and having rising therefrom the standard 3 terminating in an inwardly disposed head 4, having at each corner a journal 5.

Slidably and rotatably journaled in one 60 of said members 5 is the clamp spindle 6 having the tripod or clamping member 7 at the lower end and the operating head 8 at the upper end, and being urged downward into clamping position by the spring 9, 65 whose tension is controlled by the adjustable nut 10 at the top of the journal. Similarly slidably and rotatably mounted in the other journal, is the drive shaft 11, bearing on its upper end the operating handle or crank 70 12 and having its lower end provided with the notch or groove 13, said spindle being pressed downwardly into operative position as by the spring 14 bearing against the collar 15 on the spindle or shaft. 75

Disposed on the base coaxial with the spindle or shaft 11, is a gear 16 carried by the shaft 17 rotatably mounted in the base 1, while meshing with the gear 16 is a second gear 18 having an equal number of teeth to 80 synchronously rotate with the gear 16, said gear 18 being supported on the shaft 19 which is slidably and rotatably supported by the base 1, a lever 20 being pivoted to the base and having a forwardly extending operating portion and a rearwardly extending portion engaging the shaft 19 whereby depression of the forward end of the lever 20 will serve to raise the shaft and gear. This gear 18 is adapted to serve as a lens supporting table and is preferably provided with the usual lens receiving pad 21. The lens being placed in position on the pad when the gear is in lowered position and depression of the lever 20 then bringing the lens 85 upward into correct engagement with the cutting point 22. This cutting point is supported by the spindle 23, which is cut away to span the lens and bring the point exactly at the axis of the spindle, the spindle being 100 rotatably mounted in the yoke 24 and capable of adjustment by turning the knurled head 25 on the spindle, a spring pressed locking plunger disposed as at 26 serving to lock the spindle in desired rotatably adjusted position. 105

It will thus be seen that by rotation of the spindle the cutting point 22 may be set

at any desired angle relative to the surface on which it is to operate and on account of its position at the axis of the carrying spindle, the position of the point will remain 5 constant and without lateral movement irrespective of the angular movement.

The yoke 24 carrying the cutter spindle is supported by the standard 27 rigidly and unyieldingly secured to the slide 28 which 10 extends transversely of the base, having the slot 29 through which the shafts 17 and 19 depend, and being retained in position as by the cap plate 30 on the under side of the base.

15 Secured to the slide 28 at the opposite side of the machine from that to which the standard 27 is located, is the block 31 having at its top the guide way 32 in which is slidably mounted the gage and contact plate or 20 shoe 33, whose position relative to the block is controlled by the adjusting nut 34, interlocking with the depending flange 35 on the outer end of the contact plate or shoe. A series of graduations 36 on one of the members and an indicating line or pointer 37 on the other, serves to indicate the adjustment of the contact member.

For coöperation with the contact member or shoe 33 and to control the shape of mark 30 or cutting line inscribed on the lens by the point 22, I employ my improved removable former 38 having the central bore or aperture 39 and the supplemental aperture, socket or key-way 40. In use the former 38 is placed on the gear 16 with the reduced upper end 41 of the shaft 17 fitting within the aperture 39 and the pin or key 42 engaged in the aperture or key-way 40 to lock the former in predetermined position on the 40 gear 16. It will be noted that the upper end of the member 41 is formed with the rib or projection 43, adapted to interlock with the lower end of the actuating spindle 12, when the same is in lowered position, but capable 45 of ready disengagement therefrom upon lifting of the spindle 12.

It will thus be understood that under ordinary conditions the spindle 11 is held in depressed position interlocking with the upper end of the shaft 17 by the spring 14, whereby upon rotation of the handle 12 the gear 17 and thus the table gear 18 will be rotated, the table carrying with it the lens and shifting the lens beneath the stationary 55 cutting point 22, while the former moves with the gear 16 and on account of its contact with the shoe or plate 33 draws the cutting plate inward by its camming action, or allows it to move outward with the slide 60 28 actuated by the spring 44 which tends to force the slide outward and to hold the contact shoe 33 against the former 38.

When it is desired to change formers it is merely necessary to raise the spindle 11, locking it in raised position if desired, as by

the latch member 45 engaging the collar 15, when the former may be lifted upward off the gear 16 as indicated in Fig. IV, and a new former substituted.

In Fig. V, I have illustrated a slight 70 modification of my invention, in which the gear 16 is secured on the lower end of the spindle 11 and movable vertically therewith in place of being secured to the base, as is clearly illustrated in Fig. V, the shaft 17 75 being provided on the base for interlocking with the shaft 11 below the gear and the former being keyed or splined onto the shaft 17, as indicated in the dotted lines in Fig. VI.

In this form of my invention the slide 28 80 is located on top of the base 1 in place of extending therethrough and is provided at its inner end with the adjustable contact shoe 46 whose position is controlled by means of the adjusting screw 47, said contact shoe 46 having the pointer 48 extending outwardly over the graduated or scale portion 49 of the slide for indicating the adjustment of the contact member, the cutter and contact shoe in this form of my invention thus operating together in place of being opposed, as in the form previously described, the construction and general advantages and operation of the cutter being otherwise the same.

95 From the foregoing description taken in connection with the accompanying drawings the construction, operation and advantages of my improved cutter should be readily apparent and it will be seen that I have provided an improved construction in which the former is entirely independent of the lens clamping mechanism, in which the former may be readily interchanged as desired in an extremely simple and efficient 100 manner, in which the entire machine embodies but two gears, thus eliminating lost motion, multiplicity of parts and liability of parts getting out of true or alinement one with the other. In addition it will be seen 110 that I have provided an improved simple construction by which the diamond may be set to be normal to any surface to be operated upon, in which the diamond or cutting point is very rigidly and satisfactorily held 115 and in which the height of the entire machine may be made considerably less than is possible with present machines in view of the economy of space and general compact arrangement of parts rendered possible 120 through my construction.

I claim:

1. A cutter, including a base, a pair of intermeshing gears rotatably mounted on the base, a former carried by one of said gears, the other being adapted to support a lens, and a cutter guided by the former and movable over the other gear for operatively engaging a lens thereon.

2. A lens cutter, including a base, a pair 130

of intermeshing gears mounted on the base, a lens support carried by one of the gears, a former rotatable with the other of said gears, and a slide mounted on the base having a part for engaging the former and a second part for cutting a lens on the lens support to the shape of the former.

3. A lens cutter, including a base and a slide carried thereby, a cutter mounted on the slide at one end thereof, a rotatable lens support and former, and means opposite the cutter for shifting the slide as the former is rotated to cut the desired pattern on the lens.

4. In a lens cutter, the combination with a base, of a pair of non-axial gears rotatably supported thereby, a former supported for rotation with one of the gears, and lens bearing means disposed for rotation with the other of the gears, a transversely movable slide mounted on the base, and former engaging and lens cutting means carried by the slide for coöperation with the respective gears.

5. A lens cutter including a base, a slide supported by the base and bearing a cutter at one end, a lens table rotatably mounted on the base, means for rotating the table and lens carried thereby, and means at the end of the slide opposite the cutter for shifting the slide to control the position of the cutter during the rotation of the lens.

6. A lens cutter, including a base, a pair of shafts rising from the base, means for synchronously rotating said shafts, a former on one of the shafts, a lens holder coöperating with the other shaft, a slide on the base, and a contact shoe adjustably mounted on the slide for engagement with the former

to control the position of the slide relative to the lens holder.

7. In a lens cutter, the combination with a driving shaft, of a second shaft driven thereby, a clutch connection between said shafts, a former removably keyed to the driven shaft, and means for holding the shafts interlocked to retain the former in position.

8. A lens cutter, including a base, a pair of intermeshing horizontally alined gears carried by the base, means for rotating the gears, a former carried by one of the gears and a lens support carried by the other, a transversely shiftable slide on the base having an adjustable contact shoe engaging the former, means for resiliently retaining the shoe in engagement with the former, and a yoke on the slide spanning the gear and carrying an adjustable cutting device overlying the lens holder, substantially as and for the purpose described.

9. In a lens cutter, the combination with a lens holder, of a yoke spanning the lens holder, a cutter bar rotatably supported by the yoke and having a relieved portion overlying the lens holder, a cutter carried by the bar and having its point disposed in the axis of rotation thereof, and means for locking the bar in desired rotatively adjusted position.

In testimony whereof I affix my signature in the presence of two witnesses.

ARTHUR A. ARNOLD.
